EXPANSION PLUG FOR INTERNAL
COMBUSTION ENGINES

Sidney E. Pearson, Kansas City, Kans.

Application June 8, 1939, Serial No. 278,069

1 Claim. (Cl. 220—25)

This invention relates to plugs for openings formed in walls of bodies such as internal combustion engines, tanks, boilers and similar devices where plugging the opening is possible only by introducing the closure from one side.

One of the important aims of this invention is to provide an expansion plug for internal combustion engines that may be moved to position where but a limited amount of space is available and where it is usually necessary to dismantle parts of the engine per se or the equipment associated therewith.

Heretofore plugs of the character embodying this invention have been driven or similarly forced to position and the inherent strength of the cover or wafer employed to hold the plug against accidental displacement. Leakage occurs around expansion plugs for internal combustion engines where the seal is not complete and positive. It is one of the objects of this invention to provide unique plug structure of the character which may be positioned without the use of special tools and that may be anchored so that no objectionable projecting parts are present.

A still further object of this invention is the provision of an expansion plug of the aforementioned character which has an anchor composed of a pair of super-imposed parts, which parts are movable through the opening to be plugged when the anchor is collapsed.

A further aim of this invention is to provide a plug of the aforementioned character which has a specially formed and disposed stem, the nature of which presents a guide to the operator when the plug is being moved to the operative position.

Minor objects of the invention will appear during the course of the following specification, referring to the accompanying drawing wherein:

Figure 1 is a view of a portion of an engine block having the expansion plug embodying this invention attached thereto.

Fig. 2 is a fragmentary side elevational view of a portion of an internal combustion engine in place, illustrating the plug along the section line II—II of Fig. 1.

Fig. 3 is an inside face view of a portion of an engine block, illustrating the manner of disposing the anchor to hold the plug in place; and,

Fig. 4 is a cross sectional view through an expansion plug embodying a modified form of the invention.

Difficulty has arisen in applying expansion plugs to internal combustion engines because of the limited amount of space left between parts of the automobile and the wall to which the

plug is to be attached. The limited space between engine block 8 and dash 10 of the automobile is illustrated in Fig. 2. Obviously, tools cannot be used in applying the plug since there is barely space enough for the introduction of the operator's hand between wall 12 and dash 10. Such situations will be found at other locations on engine block 8 and therefore the plug assembly embodying this invention becomes advantageous because of the ability to move the same to the operative position without the necessity of disassembling parts to afford additional room.

Those skilled in the art will readily understand that the expansion plug may be used in closing 15 the openings through walls of tanks, boilers and other articles where it is impossible to reach the inner face for the purpose of attaching an anchor.

Wall 12 is provided with opening 14 and it is 20 this opening which must be effectively sealed so that water 16 within the jacket of the engine 8 will not escape.

In the preferred embodiment of the invention, 25 the plug comprises a recessed cover 18 formed of sheet metal and provided with a continuous annular flange 20, the inner face of which is in opposed relation to the outer face of wall 12 around opening 14.

The annular shoulder 22 formed between the 30 bottom 24 of cover 18 and flange 20 thereof, is slightly less in diameter than the diameter of opening 14 and therefore, when cover 18 is in place, it is secured against accidental lateral movement by this said shoulder 22.

Cover 18 has a perforation 26 at the axis 35 thereof which passes the specially formed stem 28. A specially formed anchor is carried by one end of stem 28 and comprises a laterally extending head 30 which is rigid to stem 28 and which turns therewith. The other end of stem 28 has a laterally curved portion 32 which is in opposed relation with head 30. Thus, when the anchor is within the cavity beyond opening 14, it is possible for the operator to determine 40 the exact position of head 30 by viewing the curved portion 32.

Finger 34 is mounted upon stem 28 adjacent to head 30. This finger is free to rotate about stem 28 and the action of gravity holds the same 45 in a downwardly extending position, such as shown in Figs. 2 and 3 when the plug is in place.

Stem 28 is screw-threaded along a greater portion of its length and a thumb nut 36 is in screw-threaded engagement with the threads on stem 50 28 for the purpose of drawing together cover 18

and elements 30 and 34 forming the anchor. Nut 36 is specially formed so that no part thereof will project beyond the cavity formed in cover 18. When nut 36 is forced to the operative position, shown in Fig. 2, the notch 38 formed in stem 28 is spaced outwardly from the outer face of nut 36 and through its weakening action on stem 28, the curved portion 32 of the stem may be broken away.

A washer 40 is positioned between flange 20 and the outer face of wall 12, and another washer 42 circumscribes stem 28 and lies between the inner face of nut 36 and the outer face of cover 18. Thus, opening 14 is completely sealed and the escape of water from within the cooling jacket of motor 8 is precluded.

From the foregoing, it will be obvious that when nut 36 is adjacent to the curved end of stem 28 and when head 30 and finger 34 are in superimposed relation, it will be possible to manipulate the plug assembly so that the anchor will be within the cavity formed in engine 8.

Turning the stem about its axis will readily dispose head 30 and finger 34 in the proper opposed relation by moving the same through paths of travel indicated by the arrows in Fig. 3. When parts 30 and 34 are so positioned, nut 36 is tightened and the cover 18 is securely held in place.

An expansion plug embodying a modified form of the invention is illustrated in Fig. 4. The perforated sheet metal dish-shaped cover 50 is similar to the one previously described and has a central perforation 52 formed therethrough.

Head 54 is a single strip of metal extending diametrically across the opening in wall 12 of the engine. This head 54 has a perforation 56 midway between the ends thereof through which passes the reduced length of coupling bolt 58. Bolt 58 has an annular shoulder 59 that bears against one face of head 54 when the parts are assembled and an internally threaded socket 60 extends inwardly from the end of larger diameter of bolt 58. This bolt 58 is externally threaded inwardly from both ends thereof and a nut 62 bears against the other side of head 54.

Wing nut 64 threaded upon the end of larger diameter of bolt 58 bears against the outer face of cover 50 and it is obvious from an understanding of the device as illustrated in Fig. 4, that a tightening of wing nut 64 will draw together all of the parts just mentioned.

When manipulating nut 64, bolt 58 sometimes accidentally turns. To preclude such action and to afford a member with which to hold head 54 in place while cover 50 is being moved to the operative position, key 66 is provided, one end of which is externally threaded to fit into threaded socket 60. This key 66 is L-shaped and provides a handle for the operator to hold when the wing nut is being manipulated.

Manifestly, expansion plugs of different appearances than those illustrated in the accompanying drawing may be made without departing from the spirit of the invention and scope of the appended claim.

Having thus described the invention, what is claimed as new and desired to be secured by Letters Patent is:

A plug for closing an opening through the wall of an engine block or the like, comprising a dish-shaped, perforated cover provided with an annular flange adapted to bear against the marginal edge of the wall around the opening to be closed when the body of the cover is within the opening; a perforated head extending substantially diametrically across the opening in spaced relation to the cover; a coupling bolt provided with an internally threaded, axial socket at one end thereof and means at the other end for pivotally engaging the head at the perforation thereof; external screw-threads on the said bolt at the socketed end thereof; a nut on the bolt movable toward and from the outer face of the innermost portion of the cover; and an L-shaped key having external screw-threads at one end in screw-threaded engagement with the internal threads of the bolt, said nut being below the plane of the annular flange when the same is forced against the cover.
